UNITED STATES PATENT OFFICE.

LLEWELLYN B. SHULTZ, OF ST. LOUIS, MISSOURI, ASSIGNOR TO PILLEY PACKING & FLUE BRUSH MANUFACTURING COMPANY, OF ST. LOUIS, MISSOURI, A CORPORATION OF MISSOURI.

SCRAPING TOOL.

Application filed September 9, 1926. Serial No. 134,362.

My invention relates to a scraping tool and particularly to one adapted to remove deposits from the inner surfaces of holes of small bore, such for example, as the guide 5 openings for valve stems of internal combustion engines.

The object of my invention is to provide a tool for the purpose described, which may be readily adjusted to operate on bores of 10 different diameters and which will be self sharpening.

In the accompanying drawings, which illustrate one form of tool made in accordance with my invention, Figure 1 is a side elevation; Figure 2 is a section taken on the line 2—2 of Figure 1; and Figure 3 is an enlarged section taken on the line 3—3 of Figure 1.

The stem 5 of the tool is adapted to be held in the chuck of the drill by means of which 20 the tool is rotated. Threaded into the stem 5 is a rod 6 firmly held in position in the stem by a lock nut 7. Secured to the upper end of the rod is a blade holding sleeve 8. Sliding on the rod is a second blade holding sleeve 9. 25 These sleeves 8 and 9 are each provided with a bore 10 terminating in a conical end 11 and are arranged on the rod with the open ends of the bores toward each other so as to receive the ends of the scraping blades 12. 30 The scraping blades are formed of flat strips of tempered steel, preferably four in number, and may be sprung outwardly at the central parts to a greater or lesser degree to fit different sized holes by movement of the 35 sleeve 9 along the rod 6. In order to secure the longitudinal movement of the sleeve 9 I

thread on the lower end of the rod a collar 13 provided with flattened faces 14 for engagement with a wrench. A lock nut 15 serves to secure the collar in position after 40 the proper adjustment has been made.

The conical ends 11 of the bores 10 force the ends of the blades firmly against the rod 6 and thus provide a simple and effective means for binding the rod, sleeves and blades together 45 so that parts of the tool will rotate together without relative movement of the parts. It will be evident that the edges of the blades will form scraping faces substantially perpendicular to the wall of the bore operated 50 on, and that the tool will be in effect self sharpening as the wear, which will be wholly on the corners of the blades, will in no way affect the relation of the scraping faces to the walls operated upon. 55

Having fully described my invention, what I claim as new and desire to secure by Letters Patent of the United States is:

In a device of the class described, the combination with a rod, of a pair of sleeves on 60 said rod, each provided with a bore of greater diameter than the rod and terminating in a restricted portion, bendable scraping blades having their ends between said rod and sleeves and clamped to the rod by said restricted portion, and means for moving said sleeves toward and away from each other to spring the scraper blades and thus vary the effective diameter of the tool. 65

In testimony whereof, I hereunto affix my 70 signature, this 7th day of September, 1926.

LLEWELLYN B. SHULTZ.
